CLAIM

The ornamental design for a clamp meter with pistol grip handle, as shown and described.

DESCRIPTION

FIG. 1 is a rear perspective view of a first construction of a clamp meter with pistol-grip handle of the present invention.

FIG. 2 is a front view of the clamp meter of FIG. 1.

FIG. 3 is a right side view of the clamp meter of FIG. 1.

FIG. 4 is a left side view of the clamp meter of FIG. 1.

FIG. 5 is a rear view of the clamp meter of FIG. 1.

FIG. 6 is a top view of the clamp meter of FIG. 1; and,

FIG. 7 is a bottom view of the clamp meter of FIG. 1.

The ornamental design which is claimed is shown in solid lines in the drawings.

The portions of the design shown in broken lines are included for the purpose of illustrating environment and form no part of the claimed design. The portions of the design shown in broken lines having unequal segments illustrate the boundary of the claimed design and form no part of the claimed design.
